UNITED STATES PATENT OFFICE.

FREDERICK B. WAIBEL, OF NEWARK, NEW JERSEY, ASSIGNOR TO THE J. E. MERGOTT COMPANY, OF NEWARK, NEW JERSEY, A CORPORATION OF NEW JERSEY.

BAG-FASTENER.

1,043,177.

Specification of Letters Patent.

Patented Nov. 5, 1912.

Application filed April 3, 1912. Serial No. 688,291.

To all whom it may concern:

Be it known that I, FREDERICK B. WAIBEL, a citizen of the United States, residing in the city of Newark, in the county of Essex and State of New Jersey, have invented certain new and useful Improvements in Bag-Fasteners, of which the following is a full, clear, and exact description, such as will enable others skilled in the art to which it pertains to make, construct, and use the same, reference being had to the accompanying drawings, and to letters of reference marked thereon, forming a part of this specification.

In the use of bags, pocket books, and the like, much difficulty has been encountered in overcoming the objection raised by those who use such articles, to the spreading of the bag frame members when the contents of such bag or pocket book are such as to so 15 distend the sides as to make the closing of the bag or pocket book difficult. The principal objection arises from the fact that as ordinarily constructed, but a single catch or lock is provided in the center of the bag 20 frame members for holding the same together, leaving the ends of the frame to be sprung apart by overcrowding the interior of the bag, with resulting annoyance and loss. In order to eliminate these evils and 25 overcome these objections, I have devised a new fastener which holds the bag frame members together and which is further provided with an auxiliary catch secured to the said fastener for additionally holding the 30 members together and independently operated from the fastener.

In carrying out my invention, I make use of the structure illustrated in the accompanying drawings, in which—

40 Figure 1 represents a perspective view of a bag frame having applied thereto my improved bag fastener. Fig. 2 represents an enlarged side elevation of my improved fastener; and Fig. 3 represents a fragmentary enlarged transverse section taken on lines $x-x$ of Fig. 1, and looking in the direction indicated by the arrow.

Similar letters of reference refer to like parts throughout the specification and drawings.

45 A bag frame fastener made in accordance with my invention may be applied to any ordinary or desired form of frame. That shown in the drawings, consists of two hinged members a and b of substantially the

shape shown in Fig. 1. Near the middle portion of the frame member a , I secure the fastener or catch c , substantially as illustrated in Fig. 2 of the drawings, or in any other convenient or desired manner. 60

The fastener c preferably consists of an open-ended casing provided with two downwardly extending sides d and e , designed to embrace and hold the frame members a and b together. Extending rearwardly from the 65 side d of the fastener is an extension f , by means of which the said fastener is pivotally secured to the frame member a in any convenient or desired manner.

70 One of the sides of the fastener c preferably the one marked e is provided with an opening g to receive the headed stud h which may be secured to the frame member b in any well-known manner.

75 The fastener just described serves to hold the frame members together. In order to provide a second catch or latch for additionally holding the frame members together, which catch or latch is operated independently of the fastener c , I provide a 80 catch i , pivotally secured to the fastener c , as by means of a pivot j , said catch i being so formed as to provide an opening k to receive the stud h and to have locking engagement therewith. The lower end of said 85 catch is provided with a finger piece or knob l .

90 The invention is not limited to the exact embodiments shown, but may be modified in various ways in the scope of the following 95 claims.

I claim:

1. In combination, two members movable relatively to each other, a fastener secured to one of said members embracing and holding said frame members together, and a locking device secured to said fastener having locking engagement with one of said frame members for additionally holding said fastener and members together and independently operated from the fastener. 100

2. In combination, two members movable relatively to each other, a fastener secured to one of said members for holding said frame members together, a stud secured to the other member and a catch for additionally holding said frame members together pivotally secured to the said fastener and adapted to engage with said stud and independently operated from the fastener. 105 110

3. In a purse or bag fastener, the combination with a pair of hinged frame members, of a fastener pivotally secured to one of said frame members embracing and holding said members together, and a catch for additionally holding said members together pivotally mounted upon said fastener and operated independently from said fastener.
4. In a purse or bag fastener, the combination of a pair of hinged frame members, of a fastener pivotally secured to one of said frame members adapted to embrace and hold said members together, a stud secured

to the other frame member and a locking device pivotally secured to said fastener and having locking engagement with said stud for additionally holding said frame members and independently operated from said fastener. 5

This specification signed and witnessed 20 this 29th day of March, 1912.

FREDERICK B. WAIBEL.
